A. Patterson,

Lock Strike.

N° 17,611.

Patented June 16, 1857.

UNITED STATES PATENT OFFICE.

ANDREW PATTERSON, OF BIRMINGHAM, PENNSYLVANIA, ASSIGNOR TO J. H. JONES, OF PITTSBURGH, PENNSYLVANIA.

KEEPER FOR LOCKS AND LATCHES.

Specification of Letters Patent No. 17,611, dated June 16, 1857.

To all whom it may concern:

Be it known that I, ANDREW PATTERSON, of the borough of Birmingham, county of Allegheny, State of Pennsylvania, have invented a certain new and useful Improvement in the Manner of Constructing the Keepers of Locks and Latches Having Blunt or Round Ended Spring-Bolts; and I do hereby declare that the following is an exact and full description of my invention, reference being had to the accompanying drawings and to the letters of reference marked thereon.

The nature of my invention consists in giving to the front or face of the keeper such shape and configuration that it shall present to the protruding bolt while the door is being closed a concave line of contact or a curved incline plane.

20 To enable others skilled in the art to construct my improved keeper I will proceed to describe its construction and operation.

Figure 1 represents a double faced or reversible lock case and the keeper in their positions relative to each other when the door is closed. Fig. 2 represents a section through the two faces of the lock and keeper, the door and the jamb, showing the positions of the lock case, bolt and keeper at the instant the keeper begins to force back the bolt, the door being in the act of closing.

25 *a, a*, Fig. 1, is the case of a double faced lock case.

b, b, Fig. 1, is the keeper.

30 *c* is the face of the keeper against which the spring bolt impinges when the door is thrown to or closed. It is curved from its apex to its base toward the edge of the door, so that the inclined plane is of the greatest declination at the top and gradually decreases as it descends.

35 *e*, Fig. 2, shows the curve or concavity of the face of the keeper in section.

d, Fig. 2, is the spring bolt represented as

having just come in contact with the keeper at the steepest part of its inclined plane, and herein is the essence of my invention. The ordinary beveled keeper presents to the bolt under similar circumstances an inclined plane of uniform grade and the leverage which impels the bolt backward into the case is the same at all points. Now it is clear that a force barely sufficient to keep the bolt in motion when started back into the lock case will not be sufficient to overcome its inertia and start it in motion, especially if there be much friction between the moving parts. My improvement is designed with reference to this difficulty, which it effectually obviates by presenting a very steep incline at the first contact of the bolt. The object of the curvature is to accomplish this without making the face to project to an inconvenient and expensive extent, which it would do if the inclination were the same throughout that it is at the top.

g g, Fig. 2, is the lock case in fragment.

x x, Fig. 2, is the door on which the lock is secured.

v, Fig. 2, is the rabbet into which the door shuts.

h is the jamb on which the keeper is secured.

Other parts of the lock and its relations are similar to ordinary locks and need no description.

Having thus fully described my invention, its construction and operation, I claim as my invention and desire to secure by Letters Patent—

The use and employment in combination with a blunt or round ended latch bolt in a double faced or reversible lock case, of a keeper the face of which is curved or made concave in the manner substantially described and set forth.

ANDW. PATTERSON.
